UNITED STATES PATENT OFFICE.

WALTER W. WILLIAMS, OF BLOOMINGTON, ILLINOIS, ASSIGNOR TO WILLIAMS OIL-O-MATIC HEATING CORPORATION, OF BLOOMINGTON, ILLINOIS, A CORPORATION OF ILLINOIS.

THERMAL SAFETY CONTROL MECHANISM.

Application filed April 14, 1922. Serial No. 552,818.

My invention relates to safety control mechanisms in connection with liquid fuel feeding devices.

The object of my invention is in the provision of a safety means for controlling the action of a liquid fuel burning device; said mechanism being responsive and controlled by the heat given off by the pilot light.

Another object of my invention is in the provision of a thermal safety mechanism controlled by the pilot light, said control means consisting of an electrical contact mechanism having a portion thereof formed of bi-metallic metal, said portion capable of making or breaking an electric circuit, due to the expansion or retraction thereof, caused by the heat given off by the pilot.

In my co-pending application No. 501,486, filed September 17, 1921, I have described and claimed generally a safety mechanism controlled by the heat given off by the pilot light. However, in that instance I relied upon the expansion or retraction of a diaphragm, under varying heat pressures, to accomplish my result. In my present application I have provided means for accomplishing the same result, that is, of safety control but in a somewhat different manner.

Other objects of my invention will appear in the following specification in connection with the annexed drawings in which:

Figure 1, is a general view of the combination including the liquid fuel burning device and safety control mechanism, including the electrical circuit, therefor,

Figure 2, is an enlarged detail in plan of my specific thermal contact member.

Figure 3, is a side elevation thereof.

Figure 4, is an end elevation of Figure 3 and

Figure 5, is a plan view from below of the contact member.

Referring to the drawings, a liquid fuel burning device is shown generally at "a", this device having been described in detail in my Patent No. 1,451,798, dated April 17, 1923. It may be said generally that a series of pumps discharge an atomized fuel mixture from the jet 10. The above general statement as to the discharge of the atomized fuel mixture from the jet 10 must necessarily include a more detailed explanation as to structure utilized therefor, although said subject matter forms the basis of said Patent

1,451,798. The liquid fuel is drawn thru the fuel tube 10^a into a rotary pressure pump 10^b and raised to a considerable pressure therein before discharge thru the fuel tube 10^c to the jet 10. An electric motor 10^d supplies power for the rotary pressure pump and also for a fan 10^e, the blast from which is carried thru the housing 10^f to a point adjacent the jet 10 and supplying the proper air blast to produce a properly and efficiently atomized fuel mixture.

My present application is directed to the means for igniting this fuel mixture and for controlling the action of the device under all conditions. In my device I have always used a gas pilot light for igniting the fuel mixture and it is in connection with this pilot light that I have combined my present safety control means.

It is well known in the burner art and especially in plants used in the heating of houses that some safety means must be used therefor. Mechanical means controlled by an overflow of fuel oil in case of non-ignition have been used, and also mechanism controlled by combustion conditions or rather, the failure of combustion conditions. In my former application No. 501,486 and in the present one I have combined my safety means with the pilot light and have provided mechanism which is controlled by an element which is absolutely essential to the operation of the device.

11 shows a tube attached to the conventional gas supply, and a second gas tube 12 connects this supply with my specific thermal contact member which is shown in the detail figures on Sheet two of the drawings. Generally this thermal contact member described as "z" in Figure 1 is disposed in an angular relation to the discharge nozzle whereupon the gas flame therefrom is projected into the cone of the fuel discharge. The gas tube 12 has threaded connection at its outer end with the cap 13 on the thermal contact member. This cap projects into the base 14 of said member and has a small gas connection or jet 15 with a coned inner portion 16 of said base.

As may be seen in Figure 1, the thermal contact member has this coned portion or jet disposed angularly with relation to the fuel discharge nozzle, and the contact portions of the said thermal device project

rearwardly or rather are housed within the general housing of the blast tube of the burner. The base portion 14 has integrally cast therewith and projecting rearwardly 5 therefrom a plate 17. Projecting through and fixedly mounted at the rear end of this plate is a contact screw 18 supported and insulated by means of the nuts 19 and insulating material 20 respectively. A contact arm is attached to the plate 17 as at 10 21. This contact member is formed of thermostatic metal and has a contact portion 22 at its outer end capable of engaging the screw member 18. A guard 24 surrounds 15 a major portion of the plate and on the inner side of this guard is a strip of mica 25. This special guard means for the plate member and contact points prevents the effects of temperature variations on the thermal contact members. 20

The above specific thermal contact portion operates in the following manner:

The flame from the gas jet heats the walls of the coned portion 16 and therefore the 25 base portion. This metal is a good conductor of heat and therefore the heat is transmitted directly to the plate which is in connection with the contact arm 21. The action of this heat upon the bi-metallic contact arm, is to raise said contact arm to the dotted line position shown in Figure 3 and to hold it in such position as long as the pilot light has its flame projecting against the coned portion of the base. Likewise 30 failure of the pilot light results in a cooling of the base and therefore the contact arm, with the result that said arm contracts and its point makes contact with the insulated screw contact member. 35

40 So far I have said nothing of the electrical circuit which is included in the combination with my safety control means. Inasmuch as these various electrical elements have been partially shown and described in 45 my co-pending application No. 501,486 I do not deem it necessary to go into too great a detailed description thereof.

The time switch "T" has a vertically positioned heating coil 36 which is supported 50 by the mounting plate 37. A spring lever 38 composed of any thermal or bi-metallic metal is attached as at 39 to a bracket member 40. The upper end of the lever 38 rides beneath a lug 41 on a horizontally disposed 55 contact arm 42 firmly positioned as at 43. The outer end of the contact lever has the usual contacts 44 and 45 which have possible engagement with similar contact members 46 and 47.

60 It may be said at this time relative to the co-operation of the commercial transformer X, electrical relay switch R and fuel atomizing device 10^b, that two electrical circuits are utilized, one being a high voltage circuit 65 which includes the fuel atomizing device,

and a low voltage circuit produced by the use of the transformer which includes the relay switch for making and breaking the circuit to the atomizing device, and also the commercial room thermostat which includes the relay switch and hence controls the operation of the device directly from temperature conditions. 70

The operation of my device is as follows:

Figure 1 of the drawings illustrates the 75 position assumed by the parts when the liquid fuel is burning at the nozzle and the room thermostat has just been moved by the temperature of the room to shut off the burner. When the liquid fuel is burning at 80 the nozzle, the circuit between leads 26 and 27 is broken through Z. When the movable contact arm of the thermostat engages the right-hand contact, as shown, the secondary circuit is completed and the current travels 85 from the left-hand terminal at the bottom of the transformer X, through a lead to a binding post upon the heat switch T directly below the transformer. From thence it passes through the movable horizontal 90 arm 42 of the heat switch T to the upper left-hand contact 46 which it is shown to engage, and from thence through the lead shown in dotted line connected to the binding post second from the right at the top 95 of the panel, and thence through the lead to the connection to the movable arm of the thermostat Y, the lower end of the movable arm being in engagement with the right-hand binding post at the top of the panel, 100 and from thence through the dotted line lead, through the coils of the right-hand electromagnet 52 of the relay R and from thence through the dotted line lead to the 105 stationary contact below that magnet. With the position of the armature arm 55 as shown, the contact on the extension 60 from the under side thereof, on the lower side of the pivot, is in engagement with the right-hand stationary contact 61 below the right-hand magnet, so that the secondary current passes through this extension through the 110 metal cap at the end of the arm to the metal plate between the magnets and panel which is shown secured to the panel by the two 115 screws appearing between the electromagnets on each side of the armature arm. The current then passes from the plate through the lead shown in dotted lines extending from the left-hand screw to the right-hand terminal of the transformer. The secondary current following this path energizes the right-hand electromagnet 52 which attracts the armature arm 55 of the relay, causing it 120 to rotate about its pivot and break the contact at the top of the arm which is shown engaging the fixed contact 59 in the line circuit, and thereby breaking the circuit to the motor. At the same time this rotative movement of the armature arm about its 125 130

pivot breaks the secondary circuit, as well, because the depending contact 60 is moved away from the right-hand stationary contact and is caused to engage the left-hand stationary contact 62 at the bottom of the panel. In this position, both the primary and secondary circuits are broken and the burner is shut off. When the temperature falls sufficiently to cause the movable arm 46 of the thermostat to move to the left and complete the connection with the left-hand contact member, the secondary circuit follows the path from the transformer to the movable contact arm of the thermostat Y, as heretofore described. The secondary circuit then passes through the lead from the left-hand contact of the thermostat to the third binding post from the right at the top of the panel board and from thence through the dotted line lead to the left-hand electromagnet 51 of the relay R, through the magnet, and through the dotted line lead to the stationary contact below that magnet. The position of the armature arm when the burner is shut off moves the depending contact 60 carried thereon into engagement with the stationary contact 62 below the left-hand magnet, so that the current then passes through this depending arm to the metal plate upon which the electromagnets are mounted and through the dotted line lead from the left-hand screw of said plate to the right-hand terminal of the transformer Z. The energizing of the left-hand magnet 51 draws the armature arm over into the position shown in Figure 1, the motor circuit is thereby closed and the burner begins to function and the secondary circuit is again broken by the movement of the depending contact.

When the pilot light is extinguished, the thermostatic member 21 of Z contracts and closes the circuit between leads 26 and 27 through the ground. If the room thermostat closes the secondary circuit to start the operating of the burner in the manner just described when the gas pilot is extinguished then the burner flame fails to ignite, and a part of the current of the secondary circuit will pass from the binding post upon the heat switch T through the heating coil 36 directly below said binding post, through lead 26, thermostat Z, ground, to lead 27, thence to the right-hand stationary contact 61 in the lower part of the panel, through the depending contact 60 of the armature arm through the metal plate and lead shown in dotted lines from the left-hand screw to the right hand terminal of the transformer X. The closing of this circuit through the heating coil will cause the thermostatic member 38 at the left thereof to deform and release the support 41 below the horizontal contact arm 42 so that it will break the connection between the upper left-hand contact 46 of the heating switch and close the connection between the binding post at the right-hand of the heat switch through this movable horizontal contact arm 42 to the lower binding post on the left-hand side. The current then passes from this binding post through the dotted line lead to the right-hand binding post on the top of the panel and thence downward through the dotted line lead to the right-hand electromagnet 52 and thereby draw the armature arm to the right and break the motor circuit. During the normal operation of the burner should at any time the pilot and burner flame become extinguished, the thermostatic member 21 of Z will cool and contract closing the secondary circuit between leads 26 and 27, whereby the heating coil 36 will be energized and cause the heat switch to energize the right-hand magnet and break the motor circuit.

It is easily seen that before the burner can continue its operation the pilot light must be relighted and the time switch reset.

What I claim is:

1. In a liquid fuel burning system comprising electrical operating means for projecting air and sprayed fuel into a zone of ignition, means for igniting the fuel, a high voltage circuit including said fuel projecting means, a low voltage circuit, an electrically controlled device in said low voltage circuit for making and breaking the circuit of the said fuel projecting means, and a room thermostat included in said low voltage circuit and having a movable member for controlling the circuit to said electrically-controlled device whereby according to the degree of temperature in the room the circuit of said device will be controlled by said thermostat to cause said device to break the circuit to the fuel projecting means or to close said circuit. 90
2. In a liquid fuel burning system comprising electrically operated means for projecting air and sprayed liquid fuel into a zone of ignition, means for igniting the fuel, a high voltage circuit including said fuel projecting means, a low voltage circuit, a magnet switch for making and breaking the circuit of said fuel projecting means, the magnets whereof are in said low voltage circuit, and a room thermostat included in said low voltage circuit and having a movable member for controlling the circuit to the magnets of said switch whereby according to the degree of temperature in the room, the circuit to said magnet switch will be controlled by said thermostat to cause said switch to break the circuit to the fuel projecting means or to close said circuit. 110
3. In an oil burning heating system, electrically operated means for projecting air and sprayed liquid fuel into a zone of ignition, means for igniting the fuel, a high voltage circuit including said fuel projecting means, a low voltage circuit, a magnet switch for making and breaking the circuit of said fuel projecting means, the magnets whereof are in said low voltage circuit, and a room thermostat included in said low voltage circuit and having a movable member for controlling the circuit to the magnets of said switch whereby according to the degree of temperature in the room, the circuit to said magnet switch will be controlled by said thermostat to cause said switch to break the circuit to the fuel projecting means or to close said circuit. 125
4. In an oil burning heating system, electrically operated means for projecting air and sprayed liquid fuel into a zone of ignition, means for igniting the fuel, a high voltage circuit including said fuel projecting means, a low voltage circuit, a magnet switch for making and breaking the circuit of said fuel projecting means, the magnets whereof are in said low voltage circuit, and a room thermostat included in said low voltage circuit and having a movable member for controlling the circuit to the magnets of said switch whereby according to the degree of temperature in the room, the circuit to said magnet switch will be controlled by said thermostat to cause said switch to break the circuit to the fuel projecting means or to close said circuit. 130

- voltage circuit including said fuel projecting means, a low voltage circuit, an electrically controlled device in said low voltage circuit for making and breaking the circuit of said fuel projecting means, and a room thermostat connected to one side of said low voltage circuit and having a movable member for controlling the circuit to said electrically controlled device whereby, according to the 10 degree of temperature in the room, the circuit to said device will be controlled by said thermostat to cause said device to break the circuit to the fuel projecting means or to close said circuit.
- 15 4. In an oil burning heating system, electrically operated means for projecting air and sprayed liquid fuel into a zone of ignition, means for igniting the fuel, a high voltage circuit including said fuel projecting means, a low voltage circuit, a magnet switch 20 for making and breaking the circuit of said fuel projecting means, the magnets whereof are in said low voltage circuit, and a room thermostat connected to one side of said low voltage circuit and having a movable member 25 for controlling the circuit to the magnets of said switch whereby, according to the degree of temperature in the room, the circuit to said magnet switch will be controlled by said thermostat to cause said switch to break the circuit to the fuel projecting means, or to close said circuit.

In testimony whereof I affix my signature.
WALTER W. WILLIAMS.
